(57) **CLAIM**

The ornamental design for the sealed optics air cooled grow light, as shown and described.

DESCRIPTION

FIG. 1 is a bottom perspective view of a sealed optics air cooled grow light showing my new design;
FIG. 2 is a top perspective view thereof;
FIG. 3 is a left side view thereof;
FIG. 4 is a right side view thereof;
FIG. 5 is a front elevation view thereof;
FIG. 6 is a rear elevation view thereof;
FIG. 7 is a top plan view thereof; and,
FIG. 8 is a bottom plan view thereof.

The broken-line disclosure shown in the views is understood to represent portions of the article in which the claimed design is embodied, but which forms no part of the claimed design. Where a broken line borders a claimed surface, that broken line is understood to represent an unclaimed boundary between claimed and unclaimed portions of the article.
